+ Belknap. Attorneys

UNITED STATES PATENT OFFICE.

WILLIAM D. THOMPSON, OF DETROIT, MICHIGAN, ASSIGNOR TO HUTCHINS CAR ROOFING COMPANY, OF DETROIT, MICHIGAN, A CORPORATION OF MICHIGAN.

CAR ROOF.

Application filed May 9, 1921. Serial No. 467,893.

To all whom it may concern:

Be it known that I, WILLIAM D. THOMPSON, a citizen of the United States of America, residing at Detroit, in the county of Wayne and State of Michigan, have invented certain new and useful Improvements in Car Roofs, of which the following is a specification, reference being had therein to the accompanying drawings.

10 The invention relates to car roofs of the type known as "outside roofs", and consists in the novel construction of the weather-proofing sheets and means for securing the same as hereinafter set forth.

15 In the drawings:

Figure 1 is a cross-section through the roof;

Figure 2 is a plan view thereof;

20 Figure 3 is a section longitudinally of the roof and showing the mullion and weather-proofing cap in cross-section;

Figure 4 is a similar view of the modified construction.

25 In the construction of outside car roofs it is usual to provide metallic weather-proofing sheets which over-lie the board load-sustaining roof and which are so secured as to permit relative movement to compensate for the weaving of the car frame.

30 When the car is subjected to shocks, such as occur in shunting or by the sudden application of the brakes, there is a tendency for all of the sheets to shift longitudinally and this frequently results in tearing at the 35 points where the sheets are secured. For instance, if the sheets are secured at the eaves, but not at the ridge, there will be a twisting stress tending to tear the securing flange. The same is true if the sheets are

40 secured at the ridge and are free at the eaves. Again, if the sheets are provided with a limited freedom in all directions, they will slide back and forth under different shocks and will be injured thereby.

45 It is the primary object of my invention to hold the sheets from shifting in relation to the car frame under longitudinal shocks, while at the same time permitting a relative movement to compensate for weaving. It 50 is a further object to obtain this result with an exceedingly simple construction and one applicable to roof structures which have heretofore been used.

In detail, A is the load-sustaining board

55 roof supported upon the ridge pole B and plate C. D and D', etc. are weather-proofing sheets provided with upstanding and return-bent side flanges E, said sheets being arranged between mullions or stop strips F on the load-sustaining roof. The 60 weather-proofing is completed by caps G which embrace the mullions and are provided with return-bent flanges H for engaging the flanges E, the bends being sufficiently opened to permit of relative movement of 65 the sheets and cap. To hold the mullions F in position, they are bolted to the board roof, as indicated at I, there being preferably two bolts, one not far from the eaves or plate and the other not far from the 70 ridge. These two bolts will thus rigidly attach the mullion to the roof and take care of any stresses transmitted thereto from the roofing sheets. With my improved construction I utilize these mullions and the securing bolts therefor for holding the roofing sheets from shifting longitudinally and to this end I have provided clips J, preferably formed of sheet metal, which are secured to the bolts and extend transversely 80 of the mullions, being secured at their outer ends to the flange E of one of the sheets. The flange of the sheet on the opposite side of the mullion is free therefrom, but said sheet is secured by the flange thereof which 85 is adjacent to the next mullion. Thus each sheet is secured to a mullion so as to preclude any shifting longitudinally of the car. The clips J preferably engage recesses K formed transversely of the mullions and the 90 outer ends of the clips are downturned at L and secured to the flange E by rivets M.

In the modified construction shown in Figure 4 the clip J' is arranged beneath the mullion instead of above the same and is 95 provided with an upturned flange for engaging with the flange E. With both constructions there is nothing to prevent relative movement of the caps G and the sheets or relative movement of the sheets in 100 relation to each other, but each sheet is held from movement longitudinally of the car and is retained in a position of parallelism to the mullion.

The roof is completed by any suitable 105 rigid weather-proofing cap, such as N, and eaves weather-proofing means such as the return-bent flange O engaging a cooperat-

ing return-bent flange P on a flashing strip Q. These features are not, however, a part of the present invention.

What I claim as my invention is:

5. In an outside car roof, the combination with a load-sustaining roof, of a series of metallic roofing sheets overlying said roof, weather-proofing means between the sheets permitting relative movement thereof, and means for holding each sheet at one only of the side edges thereof from shifting longitudinally of the car.
10. In an outside car roof, the combination with a load-sustaining roof, of mullions secured thereto, roofing sheets between said mullions having upturned flanges, caps embracing said mullions and having a weather-proofing engagement with the flanges of adjacent sheets, and means for securing each sheet at one of the side edges thereof to said mullion to retain the same from shifting longitudinally of the car.
15. In an outside car roof, the combination with a load-sustaining roof, of mullions thereon, bolts for rigidly securing said mullions to said roof, weather-proofing sheets between mullions having upstanding flanges adjacent thereto, weather-proofing caps embracing said mullions and having a weather-proof engagement with said flanges, and clips for securing one of the flanges of each sheet to said bolts to prevent shifting of said sheet relative to said mullion longitudinally of the car.
20. In an outside car roof, the combination with a load-sustaining roof, of mullions on said roof extending from ridge to eaves, bolts for securing said mullions to said roof arranged respectively adjacent to the eaves and ridge, weather-proofing sheets between

mullions having upstanding return-bent flanges, caps embracing said mullions with downwardly-extending return-bent flanges embracing the flanges of the sheet and permitting relative movement, and clips secured to said bolts engaging transverse recesses in said mullions and having down-turned portions secured to the flange of one of said sheets.

45. In a car roof, the combination with a load-sustaining support, of roofing sheets upon said support, weather-proofing means between the sheets permitting relative movement thereof, and means separate from said weather-proofing means for holding each sheet from shifting longitudinally of the car roof.

50. In a car roof, the combination with a load-sustaining support, of members extending transversely thereof, roofing sheets between said members having upstanding flanges adjacent thereto, weatherproofing caps embracing said members and having a weather-proofing engagement with the flanges of adjacent sheets permitting relative movement thereof, and means connecting one of said members with an adjacent sheet to prevent shifting of said sheet relative to said member longitudinally of the car roof.

55. In an outside car roof, the combination with a load-sustaining roof, or roofing sheets upon said roof, weatherproofing means between the sheets permitting relative movement thereof, and means engaging each sheet at spaced points at one of the side edges thereof for holding said sheet from shifting longitudinally of the car.

70. In testimony whereof I affix my signature.
WILLIAM D. THOMPSON.
